UNITED STATES PATENT OFFICE.

BURLEY CLEMENS, OF MOUNDSVILLE, WEST VIRGINIA.

NON-REFILLABLE BOTTLE.

SPECIFICATION forming part of Letters Patent No. 730,003, dated June 2, 1903.

Application filed October 15, 1902. Serial No. 127,356. (No model.)

To all whom it may concern:

Be it known that I, BURLEY CLEMENS, a citizen of the United States, and a resident of Moundsville, in the county of Marshall and 5 State of West Virginia, have invented a new and useful Improvement in Non-Refillable Bottles, of which the following is a full, clear, and exact description.

My invention relates to the class of bottles 10 designated as "non-refillable;" and the object of my invention is to produce a bottle which, if not literally non-refillable, will make refilling so tedious and difficult as to be unprofitable, while at the same time the parts 15 will have such a conformation and arrangement as to enable the bottle to be manufactured by the usual methods of bottle manufacture.

To these ends my invention consists in the 20 distinctive features hereinafter particularly described, and defined in the claims.

Reference is to be had to the accompanying drawings, forming a part of this specification, in which similar characters of reference indicate corresponding parts in all the figures.

Figure 1 is a sectional elevation of the upper portion of a bottle embodying my invention with the valve in position to permit a filling of the bottle. Fig. 2 is a similar view 30 showing the valve after removal of its suspension device provided to permit the filling. Fig. 3 is a plan view of the baffle or guard partition employed in the form shown in Figs. 1 and 2, and Fig. 4 is a plan view of a baffle 35 or guard of slightly-modified form.

In forming a bottle in accordance with my invention the body A of the bottle is made with a short neck portion B, which forms the lower portion or base-section of the bottle-neck 40 and provides a valve-chamber 10, having a valve-seat b, to be hereinafter referred to. The upper portion or pouring-section B' of the bottle-neck is separately formed, as is also the guard-partition C, which constitutes 45 a retainer for a ball-valve D and a barrier to baffle any efforts toward the introduction of a wire or like instrument employed with a view to tamper with the valve D. The short base-section B of the neck, the upper pouring-section B', and the partition C are brought

into position after the valve D is in place. To unite these parts into an integral and homogeneous whole, it is only necessary that the base-section B, for instance, be heated sufficiently to give a proper degree of softness whereby when the parts B' and C are pressed against the heated section B and the whole worked together the three parts will be given a perfect union and become integral with each other and homogeneous, or, if 60 desired, the adjacent ends of both sections B' and the partition C may be heated.

The detail form of the parts is as follows:

The base-section B at its upper edge provides a seat at b' for the partition C, and the 65 pouring-section B' of the neck is rabbeted interiorly to produce a shoulder b², that bears down upon the partition C at the edge. Thus the said partition is clamped between the top of the base-section B of the neck and the 70 shoulder b² of the pouring-section. The pouring-section below the shoulder b² is of a diameter and length to encompass the partition C and overlap the base-section, as at b³. This overlapped portion is preferably tapered to 75 toward the lower edge, as at b⁴, and when the base-section is heated, as before mentioned, the said tapered lower end is worked into a union with the base-section. At the same time that portion of the partition that is 80 seated on the upper edge of the base-section will also be pressed against and worked into a union with the base-section.

The partition C in Figs. 1 and 2 is shown with semicircular slots or openings c near the 85 edge for the outlet of liquid contents of the bottle, and to guard these openings against the entrance of a wire or the like the pouring-section B' at a point above the partition is contracted to extend inward and overhang 90 said partition, as at b⁵. The internal diameter of this contracted or choked portion, as at b⁶, is such as to be within any straight line between a slot c and the mouth of the bottle-neck with a view of defeating any attempt to pass a rod or wire through a slot c from the mouth of the neck.

In the form shown in Fig. 4 the partition C' is formed with peripheral ears c² and intermediate peripheral recesses c³. When the 100

ears c^2 are secured between the base-section and the pouring-section of the bottle, as explained with respect to the partition C, the recesses c^3 form openings, establishing communication between the valve-chamber and the pouring-section in the same manner as the openings c , previously described.

The valve-seat b flares at such an angle and is of such a size as to so receive the ball-valve D as to permit the major portion of the latter to lie below the upper edge of the seat. This arrangement is designed to make it difficult to fill the bottle by submergence, since the valve tends to wedge itself, and if the bottle be tilted at an angle to permit an appreciable quantity of liquid to flow inward the valve will either roll tightly to its seat or the liquid, effective over a surface equivalent to the greatest cross-sectional area of the valve, will force the latter to a seat. Above the valve-seat b the interior surface of the base-section flares pronouncedly outward, as at b^7 , toward the openings near the edge of the partition.

In carrying out my invention the valve D is secured to the end of a suspension-wire E, which extends through an orifice c^4 , formed centrally in the partition C. Thus in filling the bottle the wire may be grasped by its hooked upper end e or be hooked over the mouth of the bottle, as indicated in Fig. 1, to hold the valve from its seat. After the filling of the bottle the wire is to be nipped off, and in order that it may be cut close to the valve the partition C is formed with a counter-bore or countersink c^5 around the orifice c^4 for the accommodation of a suitable cutting-tool. The entrance of a wire or the like through the orifice c^4 , if effected, will but press the valve to its seat.

Having thus described my invention, I claim as new and desire to secure by Letters Patent—

1. A non-refillable bottle having a valve-chamber, an upper pouring-section, and a partition-chamber interposed between the valve-chamber and the pouring-section, a partition in said partition-chamber, provided with peripheral openings, said valve-chamber having a valve-seat and being flared near its top, said partition being of equal diameter with the neck of the bottle and resting upon the top thereof with its outer periphery flush with the outer periphery of the bottle-neck, said partition-chamber being formed by the union of the top portion of the bottle-neck and an enlarged integral portion extending downwardly from the lower end of the pouring-section and having an internal annular shoulder, and telescoping over said partition and the upper end of said bottle-neck with said shoulder resting upon the partition, and a valve in the valve-chamber, said telescoping section, partition and bottle-neck being united into a homogeneous body at their point of contact, as specified and shown.

2. A bottle having a neck composed of a base-section forming a valve-chamber, and an upper or pouring section provided with an enlarged downwardly-extending portion at its lower end having a rabbet forming an internal annular shoulder in said enlarged portion, a valve in said chamber, and a guard-partition having peripheral openings and resting upon the base-section and engaged by the shoulder of the upper section, the top of said enlarged portion overhanging said peripheral openings, the said base-section being united to adjacent portions of the pouring-section and to the partition by a union that forms the said parts into an integral and homogeneous body, as set forth.

3. A bottle having its neck provided with a partition having peripheral openings, the said neck forming a valve-chamber below the partition and a pouring-section above the partition, said chamber and pouring-section being in communication at the partition through the medium of said peripheral openings, and the said pouring-section being contracted near its lower end to overhang said peripheral openings in the partition to prevent the insertion of an instrument into said peripheral openings, as set forth.

4. A bottle having a valve-chamber and a flaring valve-seat therein, a ball-valve in said chamber, and a partition integral with the neck above the valve and having segmental openings near its periphery, the upper portion of the neck forming a pouring-section and being in communication with the valve-chamber by means of said openings in the partition, the walls of the said valve-seat extending upwardly at a sharp angle to a point spaced apart from the partition about one-half the diameter of the valve, whereby to hold said valve-seat always within the walls of said valve for the purpose specified.

5. A bottle having a valve-chamber and a flaring valve-seat therein, a ball-valve in said chamber, and a partition integral with the neck above the valve and having segmental openings near its periphery, the upper portion of the neck forming a pouring-section and being in communication with the valve-chamber by means of said openings in the partition, the said valve-seat permitting the major portion of the valve to lie below the upper edge of the seat and the valve having a wire extending upward through an orifice in the partition, the said partition having a countersink at its orifice.

6. A bottle having a neck composed of a base-section forming a valve-chamber having a valve-seat; said chamber being flared near its top; an upper pouring-section having a rabbet forming a shoulder; a valve in said valve-chamber; a partition fixedly held between the base-section and the shoulder of the upper section and having peripheral openings to afford communication between the pouring-section and the valve-chamber; said

pouring-section below its rabbet being of a diameter and length to telescope over the partition and base-section; said telescoping section being beveled inwardly to an edge at its lower end, as specified and for the purpose set forth.

In testimony whereof I have signed my

name to this specification in the presence of two subscribing witnesses.
